UNITED STATES PATENT OFFICE.

EDWIN S. MORRIS AND JAMES J. MULCONROY, OF PHILADELPHIA, PENNSYLVANIA,
ASSIGNORS TO MULCONROY COMPANY, OF PHILADELPHIA, PENNSYLVANIA, A COR-
PORATION OF NEW JERSEY.

BOOT OR SHOE.

No. 895,284.

Specification of Letters Patent.

Patented Aug. 4, 1908.

Application filed October 11, 1907. Serial No. 396,912.

To all whom it may concern:

Be it known that we, EDWIN S. MORRIS and JAMES J. MULCONROY, both citizens of the United States, residing in the city and county of Philadelphia, State of Pennsylvania, have invented a new and useful Boot or Shoe, of which the following is a specification.

Our invention relates to a new and useful 10 rubber boot or shoe having a welt sole and consists in forming the upper of canvas and rubber with the edges thereof bent outwardly to extend over the welt.

It further consists of an upper formed of 15 rubber and canvas, a middle sole formed of rubber and canvas with stitching uniting the canvas of the middle sole with that of the upper and a strip of pure rubber between the insole and the stitching.

20 It further consists of novel details of construction all as will be hereinafter set forth.

Figure 1 represents a side elevation of a boot or shoe embodying our invention. Fig. 2 represents a sectional view on line x—x 25 Fig. 1. Fig. 3 represents a sectional view showing the parts in detached position for the sake of clearness.

Similar numerals of reference indicate corresponding parts in the figures. 30 Referring to the drawings, we have found in practice that in rubber boots or shoes now in use that owing to the construction it is difficult to remove old and attach new wearing soles. In addition, one of the 35 points of weakness is at the juncture of the extension or welt sole with the upper. Our invention is designed to overcome these defects and in the drawings we have shown a construction for carrying out our invention

40 but it will be evident that various changes may be made which will come within the scope of our invention and we do not therefore desire to be limited in every instance to the exact construction herein shown and described.

In practice the boot or shoe is constructed on a last as is usual and well known and no further reference need therefore be made thereto.

1 designates an inner sole which may be of 50 any desired material, the edges of which may be slightly beveled or inclined as at 2.

3 designates canvas or other suitable material which extends beneath the inner sole and upwardly a suitable distance as at 3^x into the 55 vamp or upper. Opposite the point where the edge of the inner sole 2 comes in contact with the canvas 3, we place an unvulcanized piece of rubber 4 which in the present instance is shown as triangular and which is suitably 60 fastened to the canvas, as for example by cement and gum frictioned and by rolling.

5 designates a piece of canvas or other suitable material which in the operation of forming is placed over the last and forms part of 65 the upper or vamp and the edges 6 of which are bent outwardly.

7 designates another piece of canvas which is placed adjacent the canvas 3 and which is connected preferably by a row or 70 line of stitches 8 with the canvas 5 directly at the point where the piece of unvulcanized rubber 4 contacts therewith, the ends 9 of said canvas being turned inwardly and meeting at a point substantially 10, so that a 75 double layer of canvas will be formed thereby, it being understood that the connecting means, preferably a row of stitches as at 8 will be in the bends of each of the pieces of canvas 5 and 7. This row or line of stitching 80 8 is then carefully rolled so that the rubber 4 is securely joined to the inside of the juncture of the canvas to fill up any uneven place or openings caused by the stitches. An unvulcanized piece of rubber 11 is then placed 85 around the outside of the juncture of the canvases 5 and 7 at the connecting means, preferably stitches and properly fastened by cement or gum frictioned thus positively making a water tight seal for the openings caused 90 by the stitches. A layer of rubber 12 is then laid over the canvas 5 and cemented or gum frictioned to the same with the ends 13 thereof bent outwardly.

A layer of rubber 14 which may be made with incorporated fabric 95 is placed upon the folded edges 9 of the canvas 7 which may or may not be cemented or gum frictioned fast to itself previously to this,

said layer of rubber 14 being wide enough to cover the outside of or form the welt. The wearing soles 15 are placed in position and attached to the surface of the rubber 14 by 5 cement or gum frictioned or other means and along their edges secured by mechanical means, preferably by sewing, although it will be understood that any means may be employed.

10 In the drawings, we have shown the stitches 16 for connecting the welt sole, in position.

From the above it will be understood that we form a strong, durable and light construction 15 and that while the upper is flexible on the line of the sole with the foot, it is supported by the two waterproof strips of pure rubber pieces 4 and 11 which not only add to the wearing qualities of the boot or shoe but act as a cushion to relieve jar and protect the connecting means, preferably a line of stitching 8 as well as positively sealing the same. In addition, it will be seen that the vamp or upper is connected with the extension or welt sole so that the strain will be 25 upon the upper or vamp as well as the inner sole.

Having thus described our invention, what we claim as new and desire to secure by Letters Patent, is:—

1. A rubber boot or shoe having a welt sole and an upper of canvas and rubber in one piece, the edges of both the canvas and rubber bent outwardly to extend over the 35 welt.

2. A rubber boot or shoe comprising a welt sole, an upper secured thereto, said upper consisting of rubber and canvas in one piece, the edges of both the rubber and canvas being bent outwardly to extend over the welt, a wearing sole and means for connecting the wearing sole and the welt with the portions of the upper which are turned outwardly. 40

3. A rubber boot or shoe having an insole, 45 a welt, an upper having its edges bent outwardly to extend over the welt, a middle sole, stitching uniting the middle sole with the upper and stitching uniting the outwardly bent edges of the upper, the welt and the wearing sole, and a strip of rubber between the insole and the stitching uniting the middle sole and the upper.

4. A rubber boot or shoe having an insole, 50 an upper formed of rubber and canvas, a middle sole formed of rubber and canvas, stitching uniting the canvas of the middle sole with that of the upper, and a strip of pure rubber between the insole and the stitching.

5. A rubber boot or shoe having an insole, 55 an upper formed of rubber and canvas, a middle sole formed of rubber and canvas, stitching uniting the canvas of the middle sole with that of the upper, and strips of rub-

ber on each side of the stitches serving to protect the same and acting as a cushion for the insole. 65

6. A rubber boot or shoe having an insole, a welt, an upper having its edges bent outwardly to extend over the welt, a middle sole, 70 means uniting the middle sole with the upper and means uniting the outwardly bent edges of the upper, the welt and the wearing sole and a strip of rubber between the insole and the means uniting the middle sole and upper. 75

7. In a rubber boot or shoe, an upper, a middle sole, stitching uniting the middle sole with the upper, and strips of rubber on each side of the stitching serving to protect the same and acting as a cushion. 80

8. In a rubber boot or shoe, an upper, a middle sole, means for uniting the middle sole with the upper, and strips of rubber on each side of the uniting means serving to protect the same and acting as a cushion. 85

9. A rubber boot or shoe comprising a welt sole, an upper of canvas and rubber extending from one side to the other over the vamp of the boot or shoe and bent outwardly to extend over the welt. 90

10. In a rubber boot or shoe, an upper having its edges bent outwardly to form part of the welt sole, a sole extending outwardly to form part of the welt sole, an outer sole forming part of the welt sole, means passing through the welt sole for securing the parts together, means for connecting the middle sole with the upper, and strips of rubber on each side of the connecting means serving to protect the same and acting as a cushion. 95

11. In a rubber boot or shoe, an upper having its edges bent outwardly, a middle sole with its edges bent inwardly and means for connecting the middle sole, where it is bent inwardly, to the upper, where it is bent outwardly, a sole with its edges extending outwardly to form the welt, an outer wearing sole and means passing through the welt, the wearing sole and the outwardly extending part of the upper for securing the parts together. 105

12. In a rubber boot or shoe, an upper having its edges bent outwardly to extend over the welt, a sole extending outwardly to form the welt, a middle sole, an outer wearing sole, means passing through the welt, the wearing sole and the outwardly extending portion of the upper for securing the parts together, independent means for connecting the middle sole with the upper and a strip of rubber on the inside of the connecting means serving to protect the same and acting as a cushion. 115

13. In a rubber boot or shoe, an upper having its edges bent outwardly to extend over the welt, a sole extending outwardly to form the welt, a middle sole, an outer wearing sole, means passing through the welt, the

wearing sole and the outwardly extending portion of the upper for securing the parts together, independent means for connecting the middle sole with the upper and a strip of 5 rubber on the outside of the connecting means serving to protect the same and acting as a cushion.

14. A rubber boot or shoe having an in-
sole, a middle sole with its edges bent in-
wardly, a sole with its edges extending out-

wardly to form the welt, an upper having its edges bent outwardly, means for securing the parts together and independent means for uniting the middle sole with the upper.
